UNITED STATES PATENT OFFICE.

FRANK TIFFIN TINNING AND WILLIAM KERR SUMNER TINNING, OF TORONTO, CANADA, ASSIGNEES OF ONE-FIFTH TO CHARLES WARREN IRWIN, OF SAME PLACE.

HOLDER FOR TELEPHONE-RECEIVERS.

SPECIFICATION forming part of Letters Patent No. 440,091, dated November 4, 1890.

Application filed April 21, 1890. Serial No. 348,772. (No model.)

To all whom it may concern:

Be it known that we, FRANK TIFFIN TINNING, commercial traveler, and WILLIAM KERR SUMNER TINNING, customs-house officer, both of the city of Toronto, in the county of York, in the Province of Ontario, Canada, have jointly invented a new and useful Holder for the Receiver of a Telephone, of which the following is a specification.

10 The object of the invention is to design a holder for the receiver of a telephone which may be adjusted to support the receiver level with the ear of the user of the telephone; and it consists, essentially, of securing to the wall 15 at a convenient distance from the telephone a bracket, through the end of which is fitted an extension-arm provided with fingers designed to hold the receiver, the said extension-arm being so held in the bracket as to 20 allow of its being vertically and longitudinally adjusted, as hereinafter more particularly explained.

Figure 1 is a perspective view, partially in section, of our holder with the receiver in position for use. Fig. 2 is a similar view showing the telephone-hook weighted when it is intended to have the receiver held permanently in the holder. Fig. 3 is a sectional detail.

30 In the drawings like letters of reference indicate corresponding parts in each figure.

A is the bracket secured to the wall.

B is a friction-disk secured to the end of the bracket A, and C is a corresponding friction-disk, which is held in or relieved from contact with the friction-disk B on the bracket A by the thumb-screw D. The shank of the thumb-screw D extends through a hole d in the bracket A into the friction-disk C, and 40 the thumb-screw D is so arranged that when the end of the shank is screwed home into the threaded hole e the surfaces of the disks are brought into perfect frictional contact, and the disks are thus prevented from turning in the slightest degree.

45 E is a sleeve forming part of the friction-disk C, and F is an extension-arm, which may be longitudinally adjusted in the sleeve and held in any desired position by the set-screw

50 f. On the outer end of the extension-arm F we form a cross-bar G, on which is secured

the spring-fingers g, by which the receiver of the telephone is held in position.

When it is desired to vertically adjust the extension-arm F, it is merely necessary to 55 loosen the thumb-screw D. The arm F may then be moved into position required and the thumb-screw tightened again to hold it in that position.

In Fig. 1 we show the extension-arm F 60 down out of the way, as indicated by the dotted lines. In this case the receiver is intended to be suspended on its hook on the telephone. In Fig. 2, however, we show a weight H, suspended on the hook to take the 65 place of the receiver, which is intended to be held permanently between the spring-fingers g. We attach the weight H to the telephone-box by a chain h, so that when it is desired to use the telephone it is merely necessary to 70 remove the weight H off of the hook and to place the user's ear to the receiver, which is already in position for use. From this description it will be seen that a great deal of annoyance and tediousness to the arm occasioned by the 75 user of the telephone having to hold the receiver up to his ear while waiting to receive a message will be avoided. It will also be seen that as both hands of the person receiving the message will be free he will be able 80 to make a memorandum of any message transmitted with much greater ease than at present.

What we claim as our invention is—

1. The bracket A, having a friction-disk B 85 formed on its end, in combination with the friction-disk C, the thumb-screw D, and the extension-arm F, secured in any desired position in the sleeve E by the set-screw f, substantially as and for the purpose specified. 90

2. The bracket A, having a friction-disk B formed on its end, in combination with the friction-disk C, thumb-screw D, and extension-arm F, which has formed on its outer end the cross-bar G, on which are secured the 95 spring-fingers g, substantially as and for the purpose specified.

FRANK TIFFIN TINNING.

WILLIAM KERR SUMNER TINNING.
